UNITED STATES PATENT OFFICE.

HARRISON M. VON DUYKE, OF EAST CLEVELAND, OHIO.

KEY-CARRIER.

1,255,961.

Specification of Letters Patent. Patented Feb. 12, 1918.

Application filed May 18, 1917. Serial No. 169,393.

To all whom it may concern:

Be it known that I, HARRISON M. VON DUYKE, a citizen of the United States, residing at East Cleveland, in the county of 5 Cuyahoga and State of Ohio, have invented a certain new and useful Improvement in Key-Carriers, of which the following is a specification.

This invention relates to a certain article 10 of manufacture used as a receptacle and carrier for keys or the like articles, and while the improved article embodies a number of elements of utility, the invention has particular reference to the novel construction 15 and arrangement of the parts to form a safe and convenient means for carrying keys, the same to take the place of the ordinary key-ring or key-ring and chain at present in common use.

There are a number of objectionable features common to the ordinary key-ring or the key-ring and chain. In both cases the keys are carried loose and unprotected in the pocket of one's wearing apparel, and 25 cause damage by excessive wear on the pocket. Another undesirable feature is the liability of corroding or rusting of the keys and ring, due to the fact that they are usually carried in the trousers pocket and being 30 unprotected, except by the thin fabric composing the pocket, they are subjected to the perspiration from the body and thus become damaged by rust.

The object of the present invention is to 35 provide a durable and convenient carrier which protects the keys against the moisture of perspiration and also shields them so that they will not damage the wearing apparel. The invention further provides other 40 commodities in combination with the key carrier, the article as a whole when folded and clasped being compact and adapted to be conveniently carried in any pocket.

To facilitate the understanding of the invention the accompanying drawings are 45 made a part of the specification and similar reference characters are employed to designate similar parts as referred to in the description.

In the drawings Figure 1 illustrates the 50 improved article as folded.

Fig. 2 is a view similar to Fig. 1 but with a portion of the key pocket broken away thereby showing the interior of said pocket.

Fig. 3 illustrates the article open or flat.

Fig. 4 is an end view of the article folded, and Fig. 5 is an end view partially closed, showing the particular folds.

The improved article may be made of any suitable flexible material, leather being preferable. The foundation member 1 is of substantially the shape shown in Fig. 3, being provided with a tongue member 2 and adapted to be folded and thereby forming laps or leaf members. In the embodiment 60 as shown there are three laps or leaves of substantially the same dimensions. To the exterior of leaf member 3 is attached a pocket 4. The member 1 is folded at 1^a onto itself on the opposite side from the 65 pocket 4 and has a reverse fold at 1^b, thereby forming the leaves 3, 5, and 7.

The tongue 2 is provided at its free end with a key holder 6. As shown the key holder is in the form of a metal ring, but 75 any suitable means for holding the keys may be used. The said tongue 2 is of such longitudinal dimension as to form a binder for the article, being passed around the fold 1^b, over the exterior member 7, around fold 80 1^a, and the free end with its attached key holder being inserted in the pocket formed by member 4. A spring catch of the ordinary type used on gloves is provided. This catch consists of male and female interlocking members, the female member 8 is attached to the member 4 and the male member 9 is attached to the tongue 2 in such a position that it will register with the member 8 when the article is in closed condition 85 90 as shown in Figs. 1, 2, and 4.

While the salient feature of the invention lies in the key carrier formed by the combined elements as set forth, provision is made for other commodities which have 95 been combined before in ordinary pocket folders, but which are considered new in the particular arrangement and combination as embodied in the present invention. The leaf member 5 may be utilized as a card-case and the leaf 7 may be provided with a transparent cover as used for an identification card as illustrated.

The particular folds and relative arrangement of the elements is such that the contents of the several compartments of the article are protected and when closed and clasped a compact and convenient article is provided.

It will be understood that the article may 110

be more or less elaborate in design and in material used without departing from the nature of the invention.

What I claim and desire to secure by Letters Patent is.

1. As a new article of manufacture, a key carrier comprising a foldable member provided with an exterior pocket and a connecting binding member, one end of which 10 is provided with a key holder and is adapted to enter the said pocket.
2. As a new article of manufacture, a key carrier comprising a foldable member provided with an exterior pocket, an integral 15 binding member, one end of which is adapted to enter the said pocket, a key retainer attached to the end of said binder, and a catch for engagement with the binder within the pocket.
3. As a new article of manufacture, a key carrier comprising the combination of a flexible foldable member; a pocket attached to the foldable member so as to be on the exterior of said member when folded; re-

ceptacles attached to the foldable member 25 so as to be interior when said member is folded over and onto itself; a binder member connected with said foldable member at the bottom of the exterior pocket and adapted to pass around the several folds and enter the exterior pocket; and means for locking said binder in said pocket.

4. As a new article of manufacture, a key carrier comprising the combination of a flexible foldable member; a pocket attached 35 to the foldable member so as to be exterior of said member when folded; receptacles attached to the foldable member so as to be interior when said member is folded over and onto itself; a binder member connected 40 with said foldable member at the bottom of the exterior pocket and adapted to pass around the several folds and enter the exterior pocket; a key retainer attached to the end of said binder; and means for retaining said binder in said pocket.

HARRISON M. VON DUYKE.
